UNITED STATES PATENT OFFICE.

JOHN FREDRICK QUIER, OF ONEONTA, NEW YORK.

HUB-LINER.

1,087,761.

Specification of Letters Patent. Patented Feb. 17, 1914.

Application filed April 19, 1913. Serial No. 760,263.

To all whom it may concern:

Be it known that I, JOHN FREDRICK QUIER, a citizen of the United States, residing at Oneonta, in the county of Otsego and 5 State of New York, have invented certain new and useful Improvements in Hub-Liners, of which the following is a specification.

The present invention relates to that class 10 of device known as hub liners, the essential characteristic of which is the provision of a body member adapted to be disposed between relatively movable and stationary parts whereby side play between said parts 15 under lateral strain may be resiliently taken up by reason of the flexibility of said body member. To understand the advantage of this device, it may be noted that it has been hereofore proposed to take up the lateral 20 play between two such members above mentioned by the interposition of a liner therebetween, but I have so constructed my liner that when attached in position a space is formed between the liner and its coöperating 25 member, which space permits slight movement of the liner body when force is applied thereto, thereby allowing the gradual relative adjustment of the first-mentioned parts. This materially reduces the 30 friction incident to the use of an interposed liner exactly conforming to the space representing the side play.

With the above and other objects in view, this invention consists in the construction, 35 combination and arrangement of parts all as hereinafter more fully described, claimed and illustrated in the accompanying drawings, wherein—

Figure 1 is a perspective view of a liner 40 constructed in accordance with my invention. Fig. 2 is a somewhat enlarged fragmentary view showing the application of the liner, portions of the member to which the liner is attached being broken away and 45 shown in section. Fig. 3 is a sectional view taken on the line 3—3 of Fig. 2. Fig. 4 is a transverse sectional view taken about on the line 4—4 of Fig. 3, and Fig. 5 is a fragmentary sectional view taken about on the line 50 5—5 of Fig. 2, and showing more clearly the tongue and groove connection of contiguous end portions of the body of the liner.

Throughout the following detail description, and on the several figures of the drawings, similar parts are referred to by like reference characters.

Specifically describing my device and referring to the drawings the hub liner consists of the body portion 1 which is divided into two sections 1^a and 1^b. The body portion 1 is preferably of circular form and provided with a central opening 2, each of the sections 1^a and 1^b having integral wings or arms 3 extending from their peripheral portions, the embodiment of my invention 60 showing the provision of two such arms for each section. The arms, furthermore, are bent laterally out of the plane of the body 1 for a purpose to be more fully described hereinafter. Near the outer extremity of 65 each of the arms 3 are provided a pair of openings 4 to receive the threaded ends of a yoke-member 5, which member is inserted from one side and nuts 6 provided for the ends aforesaid for clamping purposes. 70

The foregoing describes the essential features of my invention, and it will be understood that the same may be applied in various manners between relatively movable and stationary parts to take up lost motion 80 between said parts. As an illustration of the use of my invention, it will now be described as applied between the wheel and journal of a locomotive or car axle.

The numeral 7 designates the spokes of a 85 wheel 8 which is fixedly secured to an axle 9 as by means of a key 10 and to the inner side of this wheel the liner is adapted to be secured for the purpose of taking up side play between said wheel and the journal 90 box 11 most clearly seen by reference to Fig. 3. The angularity of the arms 3 with respect to the body 1, it will be noted, is determined by the number of spokes with which the wheel is provided and in order that the 95 device may be applied in the position hereinbefore set forth the body 1 is formed with the sections 1^a and 1^b, thus permitting of the insertion in place without taking the wheel off of the axle, in an obvious manner. 100 The sections 1^a and 1^b are provided with tongue and groove connection 12 at their contiguous edge portions, which connection holds said sections in rigid relation to each other. After insertion of the liner between 105 the wheel 8 and the journal box 11, the U-shaped yoke members 5 are placed around the spokes 7 and inserted in the openings 4 of the arms 3, thereby clamping the liner securely in position to the wheel. As most 110 clearly shown in Fig. 3, the lateral bend of the arms 3 holds the body portion 1 in spaced

relation to the hub of the wheel 8 which space is designated by the numeral 13, and it will be obvious that as lateral force is placed against the body 1 it will flex and resiliently take up the side play in an advantageous manner, the body yielding, of course, only when a great amount of strain is placed thereupon. The material of the liner is naturally of a resilient nature so that it will tend to maintain its normal relative rigid position indicated in Fig. 3 of the drawings. Incidental to the formation of the arms 3 grooves or recesses 3' are provided on the inner faces of the same in which grooves the spokes 7 are seated when clamping the device in position upon the wheel.

Having thus described my invention what is claimed as new is:

1. In a device of the class described, the combination of relatively movable and stationary parts, and a flexible liner member disposed and adapted to take up side motion between said parts.
2. In a device of the class described, the combination of relatively movable and stationary parts, and a flexible liner member disposed and adapted to resiliently take up side motion between said parts.
3. In a device of the class described the combination with relatively movable and stationary parts, of a liner disposed between said parts, and means for fixedly securing said liner in spaced relation to one of said parts whereby to permit resilient action of said liner.
4. In a device of the class described, the combination with a wheel and journal box,

of a liner adapted to be disposed therebetween, said liner comprising a body portion, arms formed on said body portion, and fastening members adapted to coöperate with the arms to hold the body portion in position, said arms being bent out of the plane of the body portion.

5. In a device of the class described, the combination with a wheel and journal box, of a liner adapted to be disposed therebetween, said liner comprising a body portion, arms extending from said body portion, yoke members coöoperating with the spokes of the wheel to secure the body portion in spaced relation to permit resilient movement of the body upon relative movement of the wheel and the journal box aforesaid.

6. As a new article of manufacture, a hub liner comprising a body portion of resilient material, said body portion consisting of sections having tongue and groove connection for holding said sections in rigid relation to each other, each of the sections aforesaid having one or more integral arms extending from the annular edge portions of the same, said arms being bent laterally out of the plane of the sections of the body portion, and yoke members adapted to coöperate with the arms to clamp the liner in operative position.

In testimony whereof I affix my signature in presence of two witnesses.

JOHN FREDRICK GUIER.

Witnesses:

JOHN C. HILL,
Wm. A. HILL.
